CAMSHAFT LAPPING MACHINE

Herbert S. Indge, Westboro, Mass., assignor to
 Norton Company, Worcester, Mass., a corpora-
 tion of Massachusetts

Application January 12, 1940, Serial No. 313,589

5 Claims. (Cl. 51—3)

The invention relates to abrading machines, and more particularly to a camshaft lapping machine.

One object of the invention is to provide a cam lapping machine which will more effectively lap and polish a plurality of integral cams of an automobile camshaft. A further object of the invention is to provide a cam lapping machine in which a bonded abrasive lapping element is employed. Another object of the invention is to provide a cam lapping machine in which the cam lapping arm is provided with a normally stationary lapping wheel. A further object of the invention is to provide a transversely movable lapping arm having a normally non-rotatable lapping element at one end and a follower roller actuated by a master cam adjacent to the other end of the arm.

A further object of the invention is to provide for intermittently indexing the normally non-rotatable lapping element. A further object of the invention is to provide a lapping element indexing mechanism which is actuated by and in timed relation with the transverse movement of the lapping arm. Another object of the invention is to provide automatically actuated means to withdraw the lapping arm to an inoperative position after a predetermined lapping operation has been completed. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a cross sectional view through the improved camshaft lapping machine;

Fig. 2 is a fragmentary perspective view, on an enlarged scale, of one of the cam lapping arms and the actuating mechanism therefor;

Fig. 3 is a fragmentary side elevation, on an enlarged scale, of the lapping wheel indexing mechanism as shown in Figs. 1 and 2;

Fig. 4 is a fragmentary perspective view, on an enlarged scale, of a modified form of indexing mechanism for the lapping element; and

Fig. 5 is a similar fragmentary perspective view of the modified cam lapping element indexing mechanism.

A camshaft lapping machine has been illustrated in the drawings comprising a base 10

which supports a longitudinally reciprocable work supporting table 11. The table ways are provided between the base 10 and the table 11 which in the preferred form are of an anti-friction type. The base 10 is provided with a plate 13 which is fixed to the base and is provided on its opposite edges with parallel grooves 14 and 15 which serve as inner raceways for a pair of spaced rows of anti-friction balls 16 and 17, respectively. A cage 10 (not shown) is provided between the races to space the balls 16 and 17 longitudinally as desired. The above parts form antifriction ways whereby the table 11 together with a headstock 18 and a footstock (not shown) may be readily reciprocated during the lapping operation.

The arrangement of the headstock and footstock and associated parts is substantially identical with that shown in my prior Patent No. 2,166,009 dated July 11, 1939, to which reference may be had for details of disclosure not contained herein.

Lap arm support

It is desirable to provide a movable support for a plurality of cam and bearing lapping arms so that they may be simultaneously and rapidly moved into an operative or inoperative position, as desired. A pair of spaced supporting arms 20, only one of which has been illustrated in the drawings (Fig. 1), are mounted on a rock shaft 21 which is supported in bearings on the rear of the machine base 10. The arms 20 are provided with horizontally extending portions which are connected by two parallel spaced bars 22 and 23 which serve as slide bars or ways for supporting a plurality of lapping arms to be hereinafter described.

The lapping arm assembly supported by the arms 20 is arranged automatically to be moved to and from an operative position to facilitate loading of camshafts into the machine and removing them therefrom after a lapping operation has been completed. In order to move the entire lapping assembly to an inoperative position, a fluid pressure mechanism is provided comprising a fluid pressure cylinder 24 which is pivotally connected by means of a stud 25 with the base 10 of the machine. A piston 26 is slidably mounted within the cylinder 24 and is connected to one end of a piston rod 27. The other end of the piston rod 27 is connected by a stud 28 with an arm 29 pivotally mounted on a shaft 30 supported within the base 10. The arm 29 is provided with a stud 31 which is connected to one end of a link 32. The other end of the link 32 is

connected by a stud 33 with the adjacent ends of a pair of toggle levers 34 and 35. The toggle lever 34 is connected at its other end by means of a stud 36 with the base 10 and the toggle lever 35 is connected by a stud 37 with an arm 38 which is fixedly mounted on the rock shaft 21 and is arranged to rock the shaft 21 together with the arms 20 and all of the cam and bearing lapping arms together with their supporting and actuating mechanisms either into or away from an operative position. The levers 29, 32, 34 and 35, as shown in full lines in Fig. 1, are in a position to hold the arm 38 and the arms 20 together with the entire lapping arm assembly in an operative position.

When a lapping operation has been completed, fluid under pressure is admitted to the cylinder 24 to cause the piston 26 and the piston rod 27 to move toward the right (Fig. 1) so as to shift the lever mechanism above described to rock the arm 38, the rock shaft 21, together with the arms 20, in a clockwise direction (Fig. 1) to move the entire lapping arm assembly to an inoperative position.

A fluid pressure system is provided to control the admission of fluid under pressure to the cylinder 24. A pump 39 within the base 10 of the machine draws fluid through a pipe 40 from a reservoir 41 within the base 10 and passes fluid under pressure through a pipe 42 to a control valve 43. The valve 43 is of a balanced piston type having a valve stem 44 which is provided at its outer end with a spool-shaped member 45 and is connected by means of a pair of diametrically opposed studs or pins 46 mounted on a yoked end of a control lever 47. The control lever 47 is pivotally supported on a stud 48 which is carried by a bracket 49 fixedly supported on the front of the base 10 of the machine. A plurality of valve pistons 52, 53 and 54 are formed integral with the valve stem 44. Fluid under pressure passing through the pipe 42 enters a valve chamber 55 located between the valve pistons 53 and 54 and passes out through a pipe 56 into a cylinder chamber 57 to cause the piston 26 to move toward the left (Fig. 1) to shift the lapping arm support 20 in a counterclockwise direction (Fig. 1) to position the cam and bearing lapping arm in an operative position.

During the admission of fluid under pressure to the cylinder chamber 57, fluid is exhausted from a cylinder chamber 58 at the other end of the cylinder 24, through a pipe 59, a valve chamber 60 located between the valve pistons 52 and 53, and out through a pipe 61 which exhausts into the reservoir 41. A fluid pressure relief valve 62 is connected by a pipe 63 with the pipe 42 and serves to by-pass any excess fluid under pressure if the pressure within the pipe line 42 for any reason increases over the desired and predetermined operating pressure.

After a lapping operation has been completed, the control lever 47 is rocked in a counterclockwise direction (Fig. 1) to shift the valve 43 into a reverse position so that fluid under pressure from the pump 39 passing through the pipe 42 enters the valve chamber 60 located between the valve pistons 52 and 53 and passes out through the pipe 59 into the cylinder chamber 58. The admission of fluid under pressure to the cylinder chamber 58 causes the piston 26 and the piston rod 27 to move toward the right (Fig. 1), which movement serves through the lever mechanism above described to rock the arm 38, the rock shaft 21, and the arms 20 in a clockwise direc-

tion so as to move the entire lapping arm assembly to an inoperative position. During this movement fluid within the cylinder chamber 57 exhausts through the pipe 56, through the valve chamber 55 located between the valve pistons 53 and 54, and through the pipe 61 into the reservoir 41.

Headstock

The headstock 18 is provided with a rotatable spindle (not shown) which is supported in suitable bearings within the headstock frame. The headstock spindle may be rotated from any suitable source of power, such as an overhead belt drive or a self-contained electric motor. In the preferred construction, an electric motor 65 is mounted within the base 10 of the machine. The motor 65 is provided with a driving pulley 66 which is connected by multiple V-belts 67 with a pulley 68 on the headstock 18. The headstock construction has not been illustrated in detail in the present application, since this headstock is not considered to be a part of the present invention and, furthermore, is identical with that shown in the prior U. S. Patent No. 2,092,734 to H. S. Indge and G. E. Hulbert dated September 7, 1937, to which reference may be had for details of construction not found herein.

A plurality of bearing lapping arms 70 (Fig. 1) are provided, one for finishing each main bearing on the camshaft being lapped. These lapping arms 70 are pivotally supported on a stud 71 which is in turn supported on the upper end of an arm 72. Each of the lapping arms 70 carries on its forward end, lapping elements 73 and 74 which are arranged to engage a main bearing 75 of a camshaft 76 to be lapped. The lapping elements 73 and 74 are supported on pivotally mounted, toggle actuated arms, the details of which will not be described herein since these arms 70 are identical with those disclosed in my prior U. S. Patent No. 2,166,009 dated July 11, 1939. The lapping elements 73 and 74 carried by the arms 70 are moved to and from operative positions by means of a fluid pressure mechanism comprising a cylinder 77 having a piston 78 slidably mounted therein. The piston 78 is connected by means of a piston rod 79 to actuate the toggle lever so as to close the lapping element into operative engagement with the work piece before a lapping operation and to remove them therefrom after the lapping operation has been completed.

Fluid under pressure from the pump 39 within the base 10 of the machine passes through the pipe 42 and through a pipe 80 to a manually operable control valve 81. The valve 81 is preferably a rotary type valve having a valve rotor 82 rotatably supported within the valve casing. Fluid under pressure passing through the pipe 80 passes through a valve chamber 83 formed in the valve rotor 82 and is forced out through a pipe 84 which connects with a pipe or manifold 85 extending longitudinally of the machine. The manifold 85 is connected by means of flexible pipes with the hydraulic actuating mechanism for the lapping arms 70 (only one of the pipes and arms having been illustrated in the present case). Fluid under pressure within the manifold 85 passes through a flexible pipe or conduit 86, through a passage 87, into a cylinder chamber 88, to move the piston 78 upwardly into the position shown in Fig. 1.

During this movement, fluid within a cylinder chamber 89 exhausts through a flexible pipe 90

into a pipe or manifold 91 which extends longitudinally of the machine. Fluid exhausts from the manifold 91, through a pipe 92, a valve chamber 93 formed in the valve rotor 82, and passes out through a pipe 94 which exhausts into the reservoir 41. It will be readily apparent that in the position of the valve 81, as illustrated in Fig. 1, the lapping elements 73 and 74 will be moved into lapping engagement with the main bearing 75 on the camshaft 76. When the valve rotor 82 is rotated one quarter turn, the direction of flow of fluid under pressure will be reversed to cause the piston 78 to move downwardly toward the left (Fig. 1) to remove the lapping elements 73 and 74 from operative engagement with the main bearing 75.

A suitable support is provided for the plurality of lapping arms, that is, both the bearing lapping arms above described and the cam lapping arms to be hereinafter described. One or more slides 100 (Figs. 1 and 2) are supported on the slide bars 22 and 23. The slide 100 is provided with an upper dovetailed surface which serves as a support for a plurality of lapping arms. If it is desired to reciprocate the lapping elements, a connecting rod 102 may be attached to each of the slides 100 (only one of which has been illustrated). The connecting rod 102 may be connected to a positively driven eccentric in a manner such as that shown in the prior patent to Indge and Hulbert No. 2,092,734 dated September 7, 1937, to which reference may be had for details of disclosure as to the reciprocating mechanism not contained herein.

In order to lap the cams on the camshaft 76 uniformly and to the desired finish, a master camshaft 104 is provided. The master shaft 104 is rotatably supported in suitable bearings carried by the arms 20. The master camshaft 104 is synchronously rotated with the product camshaft 76 to be lapped. The headstock 18 is provided with a sprocket 106 which is connected by means of a link chain 107 with a sprocket 108 rotatably supported on the rock shaft 21. A link chain 109 also surrounds a sprocket which is formed integral with or fixedly mounted relative to the sprocket 108 and serves to drive a sprocket 110 which is connected to rotate the master camshaft 104. An idler sprocket 111 is provided to facilitate adjustment of the tension of the chain 109. The idler sprocket 111 is adjustably supported by means of an eccentric so that it may be readily adjusted to tension the chain 109 as desired. An idler sprocket 112 which is rotatably supported on an adjustable bracket 113 serves to tension the link chain 107.

A plurality of cam lapping arms are provided, one arm for each cam on the camshaft 76 to be lapped. For the sake of simplicity of illustration, only one of these lapping arms has been illustrated in detail, since the general arrangement of these arms is substantially the same as that shown in the prior U. S. patent to Indge and Hulbert No. 2,092,734, above referred to.

A plurality of cam lapping arms 116 are provided on each of the slides 100. The cam lapping arms 116 are spaced on the slides 100 to correspond with the spacing of a plurality of cams 115 on the camshaft 76. Each of the cam lapping arms 116 is provided with a frame 117 having a lower dovetailed surface which mates with the dovetailed surface 101 on top of the slide 100. The frame 117 serves as a support for a transversely slidable bar 118. The slide bar 118 is supported by an anti-friction support comprising

spaced rollers 119 and 120. The rollers 119 and 120 are respectively supported by studs 121 and 122 carried by the frame 117. A pair of rollers 123 and 124 are supported on studs 125 and 126, respectively. The studs 125 and 126 are supported at opposite ends of a bar 127. The rollers 123 and 124 engaging the upper surface of the slide bar 118 cooperate with the rollers 119 and 120 to form an anti-friction support for the transversely movable slide bar 118. An adjusting screw 128 is screw threaded into the bracket 129 which is fixedly mounted on the frame 117 and serves to engage the bar 127 so as to adjust it in a vertical direction to take up any lost motion between the rollers 119, 120, 123 and 124, respectively.

In order to transmit a transverse movement to the slide bar 118 to uniformly lap the surface of the work piece to the desired extent, a master cam roller 130 is provided for engagement with the master cam 105 on the master camshaft 104. The master cam roller 130 is supported on a stud 131. The master cam roller 130 is maintained in operative contact with the master cam 105 by means of a spring 132 which is contained within an aperture formed within the slide bar 118 and is connected at one end to a stud 133 supported by the lapping arm 116, and at the other end is attached to a stud 134 which is fixedly mounted on the slide bar 118. The tension of the spring 132 is sufficient normally to maintain the master cam roller 130 in operative contact with the master cam 105 during the normal operation of the machine so as to transmit a transverse movement to the slide so as to produce a uniform controlled lapping action between a lapping element to be hereinafter described and the product cam 115 on the camshaft 76 to be lapped or finished.

The master cam roller 130 may be of a size equal to that of the lapping wheel 145, in which case the master cams may be identical in size and shape with the cams to be produced on the camshaft being ground. If a master cam roller of a different diameter from that of the lapping wheel 145 is utilized, then the master cams will have to be generated in order to produce the desired shape and contour on the cams being lapped.

In order to remove the cam lapping arm from an operative position after a lapping operation has been completed, a hydraulic mechanism is provided which is actuated in timed relation with the other mechanisms of the machine automatically to draw the slide 118 in timed relation with the cycle of operation. A fluid pressure cylinder 135 is fixedly mounted on the end of the slide bar 118 (Figs. 1 and 2). The cylinder 135 contains a slidably mounted piston 136 which is connected by means of a piston rod 137 with a yoke-shaped slide block 138 which supports the stud 131 and roller 130. When fluid under pressure is admitted through a pipe 139 into a cylinder chamber 140, the cylinder 135 together with the slide bar 118 will be moved toward the right (Figs. 1 and 2) to move the cam lapping element to an inoperative position. The pipe 139 is operatively connected to the flexible pipe 90 (Fig. 1) or may be connected directly to the manifold 91. In the position of the parts as illustrated in Fig. 1, the cam lapping arm 116 is shown to be in an operative position. When the rotor 82 of the valve 81 is shifted to actuate the lapping arms, fluid will be admitted through the pipe 139 into the cylinder chamber 140 to withdraw all of the cam lapping arms to an inoperative position. While only

one of the cam lapping arms has been illustrated in detail, the machine may comprise a plurality of cam lapping arms, one for each cam on the camshaft being lapped, arranged substantially the same as shown in the prior U. S. Patent to Indge and Hulbert No. 2,092,734 dated September 7, 1937.

The front end of the slide 118 carried by the lapping arm 116 supports a rotatably mounted, normally non-rotatable lapping element or wheel 145. This lapping wheel 145 is supported on a stud 146 carried at the front end of the slide 118. In order intermittently to present a fresh lapping surface during a lapping operation, an indexing mechanism is provided automatically to advance or index the lapping wheel 145 in timed relation with the transverse movement of the slide 118. A ratchet wheel 147 is rotatably supported by the slide 118 on a stud 148. The stud 148 also supports a gear 149 which meshes with a gear 150. The gear 150 is supported on a stud 151 carried by the slide 118. The gear 150 meshes with a gear 152 supported on a stud 153 which is also supported by the slide 118. The stud 153 carries a gear 154 at its other end which meshes with a gear 155 which is supported on the stud 146 and is fixedly connected to rotate the lapping wheel 145. A holding pawl 156 supported on the slide bar 118 engages the ratchet wheel and prevents it from turning in a counterclockwise direction. A ratchet pawl 157 is pivotally supported by a stud 158 carried by the lapping arm 116. When the slide bar 118 moves transversely toward the left under the influence of the master cam 195 and the master cam roller 130 (Fig. 2), the ratchet wheel 147 moves also toward the left and the pawl 157 remaining stationary, causes a partial rotation of the ratchet wheel 147 which operates through the train of gears above described to produce a partial rotation or indexing movement of the lapping element or wheel 145. Similarly, when the slide bar 118 moves toward the right, the ratchet wheel 147 is held against rotation by means of the safety pawl 156 and the ratchet pawl 157 rides idly over the ratchet wheel 147.

A modified indexing mechanism has been illustrated in Fig. 4 for indexing the lapping element or wheel 145. The lapping element 145 is rotatably supported on a stud 160 which is slidably supported in elongated slots 161 formed in the spaced supporting plates 162 and 163 of the slide 118. A ratchet wheel 164 is rotatably supported on the slide 118. A sprocket 165 is fixedly mounted to rotate with the ratchet wheel 164. The sprocket 165 is connected by means of a link chain 166 with a sprocket 167. The sprocket 167 is supported by a pair of slide blocks 168 (only one of which has been shown in Fig. 4) which are slidably supported by the slide bar 118. A peripheral surface of a friction wheel carried by the sprocket 167 frictionally engages the periphery of the lapping wheel 145. A spring 168 urges the friction wheel into engagement with the periphery of the lapping wheel to turn the same as the ratchet wheel 164 is indexed. A pawl 170 supported by a stud 171 is carried by the arm 116. It will be readily apparent from the foregoing disclosure that when the slide 118 is moved toward the left (Fig. 4) by the master cam and follower, the ratchet wheel 164 will be given a partial rotation which transmits an indexing movement to the lapping wheel 145 intermittently and automatically to present a fresh abrading surface.

A further modification has been illustrated in Fig. 5 in which a modified form of indexing mechanism has been illustrated for indexing the lapping element or wheel 145. In the modification illustrated in Fig. 5, the lapping element or wheel 145 is supported on a stud 175 carried by the slide 118. A friction indexing wheel 176 is rotatably supported by a stud 177 which is in turn supported by a vertically movable slide member 178 which is arranged to slide in a substantially vertical direction within a housing 179 formed on the forward end of the slide bar 118. A spring 180 which surrounds the stud 181 serves normally to urge the slide 178 in a downward direction to maintain the friction wheel 176 in operative frictional driving engagement with the periphery of the lapping wheel 145. A ratchet wheel 182 is fixedly mounted to rotate the friction wheel 176. A ratchet pawl 183 is pivotally supported by means of a stud 184 carried by the lapping arm 116. The pawl 183 is arranged automatically to transmit an indexing movement to the lapping element or wheel 145 each time the slide 118 is moved through a complete reciprocation by means of the master cam 195 and follower roller 130 so as to intermittently present fresh abrading surfaces into operative lapping engagement with the cam being lapped as the lapping operation proceeds.

The operation of the improved camshaft lapping machine will be readily apparent from the foregoing disclosure. A plurality of cam lapping arms 116 such as shown in the drawings, are provided, one for each cam 115 on the camshaft 76 to be lapped, and a plurality of bearing lapping arms 70 are provided, one for each main bearing 75 on the shaft 76 to be lapped. A cam-shaft 76 to be lapped is mounted in an operative position supported by the headstock 18 and footstock (not shown) in a manner substantially the same as that shown in the prior U. S. patent to Indge and Hulbert No. 2,092,734, above referred to. The control lever 47 is then shifted to swing the lapping arm assembly into an operative position (Fig. 1), after which the valve rotor 82 of the control valve 81 is shifted into the position illustrated in Fig. 1 to admit fluid under pressure into the cylinder chambers 83 of the cylinder 78 to move the bearing lapping elements 73 and 74 into operative engagement with the main bearings 75 to be lapped. At the same time, fluid is exhausted from the cylinder chambers 140 (Fig. 2) of the cylinders 135 on each of the cam lapping arms 116 to allow the released tension of the springs 132 to move the lapping elements or wheels 145 into operative engagement with the cams 115 to be lapped. The lapping operation then proceeds to the desired extent, after which the lapping elements are again moved to an inoperative position to facilitate replacement of the lapped camshaft 76 with a new shaft to be lapped.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a camshaft lapping machine, a cam

lapping arm having a transversely movable slide, a master cam roller supported adjacent to one end of said slide, a master cam engaged by said roller, said master cam and roller serving to cause a transverse movement of said slide, a piston and cylinder between said roller and slide to move said slide to an inoperative position, a normally-stationary, rotatably-mounted lapping wheel adjacent to the other end of said slide, and means actuated when fluid under pressure is admitted to said cylinder to cause a transverse movement of said slide to an inoperative position to index said lapping wheel to present a fresh abrasive surface.

2. In a camshaft lapping machine, a cam lapping arm having a transversely movable slide, a rotatable master cam roller slidably supported adjacent to one end of said slide, a master cam engaged by said roller, means to maintain said roller in engagement with said cam, means to rotate said cam to impart a transverse controlled movement to said slide, a lapping wheel supported adjacent to the other end of said slide, and means including a piston and cylinder operatively connected between said slide and roller whereby the slide may be withdrawn to an inoperative position.

3. In a camshaft lapping machine, a cam lapping arm having a transversely movable slide, a rotatable master cam roller, a slide block on said slide to support said roller, a master cam engaged by said roller, means to maintain said roller in engagement with said cam, means to rotate said cam to impart a transverse controlled movement to said slide, a lapping wheel supported adjacent to the other end of said slide, a fluid pressure cylinder on said slide, and a piston therein which is operatively connected

to said slide block whereby the slide may be moved to an inoperative position.

4. In a camshaft lapping machine, a cam lapping arm having a transversely movable slide, a master cam roller supported adjacent to one end of said slide, a master cam engaged by said roller, means to rotate said master cam to cause a transverse movement of said slide, means including a piston and cylinder operatively connected between said slide and roller whereby the slide may be withdrawn to an inoperative position, a normally-stationary, rotatably-mounted lapping wheel supported adjacent to the other end of said slide, an index mechanism including a ratchet wheel on said slide, driving connections between said ratchet wheel and said lapping wheel, and a ratchet pawl pivotally supported on said arm which is arranged to actuate said ratchet wheel to index the lapping wheel when fluid under pressure is admitted to said cylinder to move said slide to an inoperative position.

5. In a camshaft lapping machine, a cam lapping arm having a transversely movable slide, a master cam roller supported adjacent to one end of said slide, a master cam engaged by said roller, means to rotate said master cam to cause a transverse movement of said slide, a normally-stationary, rotatably-mounted lapping wheel supported adjacent to the other end of said slide, an index mechanism including a ratchet wheel on said slide, frictional driving connections between said ratchet wheel and said lapping wheel, and a ratchet pawl pivotally supported on said arm which is arranged to actuate said ratchet wheel to index the lapping wheel during the movement of said slide.

HERBERT S. INDGE.
